United States Patent Office.

A. M. KNAPP, OF RACINE, WISCONSIN.

Letters Patent No. 86,762, dated February 9, 1869.

IMPROVED NURSING-BOTTLE.

The Schedule referred to in these Letters Patent and making part of the same.

To all whom it may concern:

Be it known that I, A. M. KNAPP, of Racine, in the county of Racine, in the State of Wisconsin, have invented a new and useful Improvement in Nursing-Bottles; and I do hereby declare that the following is a full and exact description thereof, reference being had to the accompanying drawings, and to the letters of reference marked thereon, making a part of this specification, in which—

Figure 1 is an elevation of my invention, arranged for use.

Figure 2, a sectional elevation of the cap, showing the position of the valves.

Figure 3, an enlarged view of the air-valve, which regulates the pressure of atmosphere on the milk.

The nature of my invention consists in the use of a check-valve, for holding the milk in a flexible pipe; and also in the use of an air-valve, for regulating the atmospheric pressure upon the surface of the milk inside of the bottle; and, further, in graduating the bottle with such marks as will indicate the amount of milk in the bottle, and also the quantity drawn out by the child.

In order to give a correct understanding of my invention, I have marked corresponding parts with similar letters; and will now give a detailed description.

A represents a common nursing-bottle, which should be made of glass, in order that the graduating-marks, "2 oz.," "4 oz.," "6 oz.," &c., may be either blown in the glass, or marked on the outside, as seen at fig. 1, for the purpose of indicating the amount of milk in the bottle, and that which is drawn out.

This graduating-arrangement I consider important, for if it, or a similar device, is not used, the quantity of milk must necessarily be measured before it is put in the bottle, or the child must take an indefinite quantity, which is frequently deleterious to the child, especially when in the care of an inexperienced nurse.

A cap, or cover, B, is made of suitable metal, and lined on the inside with cork, D D, in order that it may be fitted closely around the bottle A, and prevent the escape of milk, or the ingress of air; and also be prevented from getting loose by ordinary use.

This cap B has a screw-valve, E, with an opening, f, through it, and arranged to prevent the air from entering the bottle A, and to regulate the quantity which is necessary to force milk through the tube C C, when the latter is drawn upon by the child.

This cap B has also a tube made fast to it by a screw-thread, as seen at m, fig. 2, for supporting an outer rubber pipe, C C, and an inner rubber pipe, H, and a glass tube, H', the pipes and tubes being used for conveying the milk from the bottle A.

The tube m is also arranged with a check; I, which is used to keep the tube C C full of milk, at such times as the child is to draw it from the bottle A.

This check-valve I, I consider important for keeping the pipe C C full, and obviating the distressing results arising from the child's drawing air into the stomach before it receives milk.

The pipe H and the pipe C C have been used before, and are therefore not considered new, but are used in connection with the valves, in order to make the device complete.

Operation.

The cap B can be removed from bottle A, so as to fill the bottle with milk, after which the cap can be replaced, and the bottle is ready for use.

Having thus described my invention, I do not claim to have originated graduated bottles, as they have been used before, but not as nursing-bottles; neither do I claim separately the pipe C and valves E I, as the former has been used in connection with nursing-bottles, and the two latter, for holding fluid in flexible pipes; but

What I do claim, and desire to secure by Letters Patent, is—

As a new article of manufacture, in combination with the bottle A, the arrangement of the pipe C and valves F I, in the manner described, and for the purpose set forth.

A. M. KNAPP.
